UNITED STATES PATENT OFFICE.

WILLIS H. THOMAS, OF PORTLAND, OREGON, ASSIGNOR OF ONE-HALF TO EINAR W. LOHSE, OF PORTLAND, OREGON.

AIR-COOLING DEVICE.

1,213,782.

Specification of Letters Patent. Patented Jan. 23, 1917.

Application filed February 14, 1916. Serial No. 78,319.

To all whom it may concern:

Be it known that I, WILLIS H. THOMAS, a citizen of the United States, and a resident of the city of Portland, county of 5 Multnomah, State of Oregon, have invented a certain new and useful Improvement in Air-Cooling Devices, of which the following is a specification.

This invention relates to devices adapted 10 for use in connection with an electric fan, whereby a current of air propelled by the fan is passed through the moistened screen, and by absorbing sufficient of the moisture will be cooled so as to lower the temperature 15 of the atmosphere a considerable amount in addition to humidifying the atmosphere. In a device of this character, certain characteristics necessary to insure the successful operation of the device are essential, 20 among which might be mentioned the following: The screen must be of a peculiar construction and arrangement in order to absorb and distribute uniformly, in the path of the air currents, the proper amount 25 of liquid. Furthermore, this screen must be of such construction that it will not retard the air currents to any considerable extent.

The main object of my invention is to provide an improved device of this character 30 in which will be embodied the characteristics just mentioned.

I accomplish the object of my invention by providing an elevated, insulated reservoir containing liquid, and supporting 35 from said reservoir a screen comprising vertical wick elements so arranged that the liquid in the reservoir will flow by gravity down the wick elements and be absorbed by the air currents passing through the 40 screen.

In the accompanying drawings: Figure 1 is a front elevation of my device with certain parts shown in section; Fig. 2 is a vertical section taken approximately in the 45 plane indicated by the line 2—2 of Fig. 1; Fig. 3 is a horizontal section taken on the line 3—3 of Fig. 1; Fig. 4 is a fragmental right side elevation of the upper portion of Fig. 1; Fig. 5 is a diagrammatic front 50 elevation showing the relative arrangement

of the screen elements and their associated parts; and Fig. 6 is a diagrammatic, horizontal section through the screen, showing an alternate arrangement of the vertical wicks.

55

An elevated wooden tank, *a*, is provided at its forward end with a longitudinal recess *b*. A metallic reservoir *c* is adapted to be nested in the tank *a* and contains the liquid, usually cold water, which is to be 60 used for cooling or otherwise impregnating the air currents blown by an electric fan *k*. A top *d* is adapted to close the upper end of the tank *a*. This construction effectively insulates the liquid in the reservoir 65 from outside heat and permits the same to remain cool for a considerable length of time. Formed in the bottom of the reservoir *c*, above the recess *b*, is a valve body *e*, in which is rotatably mounted a cylinder 70 valve *f*. The latter is provided on its outer end with an operating lever *g*. The tank *c*, valve body *e* and valve *f* are provided with ports adapted to be brought into registration with each other by the rotation of 75 the valve, so as to permit the liquid to flow from the reservoir into the recess *b* at any rate desired. The floor of the recess *b* is made with a plurality of vertical slots *h*, and the elongated bushings *i* are fixed in 80 these slots. A lower tank *j* is channel-shaped (as shown in Fig. 3) so as to permit the placing of an electric fan *k* in the position shown by the broken lines of Fig. 2. The tanks *a* and *j* are spaced from each 85 other by the supporting frame members *l*. The tank *j* is further provided with a removable cover *m* adapted to be fastened on the top of the tank by the latches *n*. The front portion of said cover is provided 90 with a plurality of vertical slots *o* in which are affixed the elongated bushings *p*, and the upper ends of the latter are flared outwardly as indicated by *q*. A screen, supported vertically between the upper and 95 lower tanks, is illustrated in Figs. 1, 3, and 5, and comprises a fabric member *r*, of considerable length and having a width equal to the inside width of the bushings *i*, *p*. Said fabric member is threaded alternately 100

through the upper and lower bushings in the manner indicated in Fig. 5, the ends of the member *r* hanging into the lower tank. This construction provides a series 5 of parallel, vertical wicks *s*, spaced apart so as to allow free passage of the air currents between them, as indicated by the arrows in Fig. 2. A wire screen *u* is laid horizontally in the recess *b*, so that it will 10 rest on the upper ends of the wicks *s*. On top of the screen *u* is a horizontal wick element *v*, preferably made of the same material as the member *r* and this wick underlies the valve so that when the latter is 15 open the liquid will drop directly on and saturate said wick.

Fixed on the forward supporting members *l* are the lateral arms *w*, *x*, provided with bearings *w'*, *x'*. A cylindrical member *y* is rotatably mounted in the bearing *w'* and is provided with a knurled nut *z* on its outer end and a collar *y'* on its inner end, which prevents longitudinal movement of said member. The member *y* is further provided with a threaded longitudinal bore. The bearing *x'* is provided with a slot *x*². A rod 4 extends through the parallel wicks *s*, and has a flattened end 5 which is adapted to slide in the slotted portion *x*² and prevent 25 rotation of said rod. The other end of the rod 4 is threaded and adapted to be engaged by the threaded bore of the member *y*. When the nut *x* is turned, the rod 4 will move longitudinally. The frictional engagement 30 between the rod 4 and the wicks *s* is sufficient to cause these wicks, which are quite flexible, to move whenever the rod 4 is moved. If desired, a more positive connection between the wicks and rod may be used. 35

40 The general operation of my device is as follows: When the valve *f* is opened, to the degree desired, the liquid will drip through onto the horizontal wick element *v* and thoroughly and uniformly saturate the latter. The capillary attractive characteristics of the wire screen *u* will cause the liquid to be deposited on the upper ends of the wicks *s*, upon which said screen rests, and the liquid will then flow by gravity down the latter. The air currents, propelled by the fan *k*, will pass through the screen and will absorb a large percentage of the moisture carried by the screen. Any surplus moisture not absorbed by the air will drip down into 50 the lower tank *j*. It will be noted that the wicks *s* are located in parallel vertical planes (see Fig. 3) and are of such width that the air currents contact with the whole surface of each wick. If it is desired to deflect the air currents in any other direction, the nut *z* is turned so as to adjust the horizontal rod 4 in the required direction, whereupon the wicks *s* will be turned correspondingly. 55

60 In Fig. 6 the wicks are arranged sym-

metrically with respect to a center line, and this arrangement causes a convergence and concentration of the air currents. 65

I claim:

1. In combination with an electric fan, a device of the character described comprising an upper tank and a lower tank rigidly spaced apart, the bottom of said upper tank being made with a longitudinal recess, a plurality of vertical wicks extending between the recess of the upper tank and the top of the lower tank, an auxiliary wick in the recess overlying the upper ends of the vertical wicks, a reservoir located in the upper tank, and a valved connection for permitting liquid to flow from the reservoir onto the auxiliary wick. 70

2. In combination with an electric fan, a device of the character described comprising an upper tank and a lower tank rigidly spaced apart, the bottom of said upper tank being made with a longitudinal recess, a plurality of vertical wicks extending between the recess of the upper tank and the top of the lower tank, a screen element in the recess of the upper tank overlying the upper ends of the wicks, an auxiliary wick overlying the screen element, a reservoir located in the upper tank, and a valved connection for permitting liquid to flow from the reservoir onto the auxiliary wick. 75

90

95

3. In combination with an electric fan, a device of the character described comprising an upper tank and a lower tank rigidly spaced apart, the bottom of said upper tank being made with a longitudinal recess, a plurality of vertical wicks extending between the recess of the upper tank and the top of the lower tank, an auxiliary wick in the recess overlying the upper ends of the vertical wicks, a reservoir located in the upper tank, 100 a valved connection for permitting liquid to flow from the reservoir onto the auxiliary wick, and means for varying the planes of the vertical wicks. 105

110

115

4. In combination with an electric fan, a device of the character described comprising an upper tank and a lower tank rigidly spaced apart, the bottom of said upper tank being made with a longitudinal recess, a plurality of vertical wicks extending between the recess of the upper tank and the top of the lower tank, a screen element in the recess of the upper tank overlying the upper ends of the wicks, an auxiliary wick overlying the screen element, a reservoir located 120 in the upper tank, a valved connection for permitting liquid to flow from the reservoir onto the auxiliary wick, and means for varying the planes of the vertical wicks. 125

5. In combination with an electric fan, a device of the character described comprising an upper tank and a lower tank rigidly spaced apart, the bottom of said upper tank

being made with a longitudinal recess, a plurality of vertical wicks extending between the recess of the upper tank and the top of the lower tank, an auxiliary wick in the recess overlying the upper ends of the vertical wicks, a reservoir located in the upper tank, a valved connection for permitting liquid to flow from the reservoir onto the auxiliary wick, a rod connecting the wicks, and means for moving said rod longitudinally.

6. In combination with an electric fan, a device of the character described comprising an upper tank and a lower tank rigidly spaced apart, the bottom of said upper tank being made with a longitudinal recess, a plurality of bushings fixed in the floor of said recess, a plurality of bushings fixed in the top of the lower tank, a plurality of wicks extending between the upper and lower bushings, an auxiliary wick in the recess overlying the upper ends of the vertical wicks, a reservoir located in the upper tank, and a valved connection for permitting liquid to flow from the reservoir onto the auxiliary wick.

7. In combination with an electric fan, a device of the character described comprising an upper tank and a lower tank rigidly spaced apart, the bottom of said upper tank being made with a longitudinal recess, a plurality of bushings fixed in the floor of said recess, a plurality of bushings fixed in the top of the lower tank, a plurality of wicks extending between the upper and lower bushings, a screen element in the recess of the upper tank overlying the upper ends of the wicks, an auxiliary wick in the recess overlying the upper ends of the vertical wicks, a reservoir located in the upper tank, and a valved connection for permitting liquid to flow from the reservoir onto the auxiliary wick.

8. In combination with an electric fan, a device of the character described comprising an upper tank and a lower tank rigidly spaced apart, the bottom of said upper tank being made with a longitudinal recess, a plurality of bushings fixed in the floor of said recess, a plurality of bushings fixed in the top of the lower tank, a plurality of wicks extending between the upper and lower bushings, a screen element in the recess of the upper tank overlying the upper ends of the wicks, an auxiliary wick in the recess overlying the upper ends of the vertical wicks, a reservoir located in the upper tank, a valved connection for permitting liquid to flow from the reservoir onto the auxiliary wick, and means for varying the planes of the vertical wicks.

9. In combination with an electric fan, in a device of the character described, an upper tank and a lower tank rigidly spaced apart, the bottom of said upper tank being made

with a longitudinal recess, a plurality of elongated bushings fixed in the floor of said recess, a plurality of elongated bushings fixed in the top of the lower tank, the lower bushings being made with flared upper ends, a screen supported between the upper and lower tanks, said screen comprising a wick adjustably threaded alternately through the upper and lower bushings, a screen element in the recess of the upper tank overlying the upper ends of the wick, an auxiliary wick overlying the screen element, a reservoir located in the upper tank, and a valved connection for permitting liquid to flow from the reservoir onto the auxiliary wick.

10. In combination with an electric fan, in a device of the character described, an upper tank and a lower tank rigidly spaced apart, the bottom of said upper tank being made with a longitudinal recess, a plurality of elongated bushings fixed in the floor of said recess, a plurality of elongated bushings fixed in the top of the lower tank, the lower bushings being made with flared upper ends, a screen supported between the upper and lower tanks, said screen comprising a wick adjustably threaded alternately through the upper and lower bushings, a screen element in the recess of the upper tank overlying the upper ends of the wick, an auxiliary wick overlying the screen element, a reservoir located in the upper tank, a valved connection for permitting liquid to flow from the reservoir onto the auxiliary wick, and means for varying the planes of the vertical wicks.

11. In combination with an electric fan, in a device of the character described, an upper tank and a lower tank rigidly spaced apart, the bottom of said upper tank being made with a longitudinal recess, a plurality of elongated bushings fixed in the floor of said recess, a plurality of elongated bushings fixed in the top of the lower tank, the lower bushings being made with flared upper ends, a screen supported between the upper and lower tanks, said screen comprising a wick adjustably threaded alternately through the upper and lower bushings, a screen element in the recess of the upper tank overlying the upper ends of the wick, an auxiliary wick overlying the screen element, a reservoir located in the upper tank, a valved connection for permitting liquid to flow from the reservoir onto the auxiliary wick, means for varying the planes of the vertical wicks, a horizontal rod connecting the wicks, and adjustable means for moving said rod longitudinally.

12. In combination with an electric fan, in a device of the character described, an upper tank and a lower tank rigidly spaced apart, the bottom of said upper tank being made with a longitudinal recess, a plurality of elongated bushings fixed in the floor of said

recess, a plurality of elongated bushings fixed in the top of the lower tank, the lower bushings being made with flared upper ends, said bushings being located in vertical 5 planes, a vertical screen supported between the upper and lower tanks, said screen comprising a fabric wick adjustably threaded alternately through the upper and lower

bushings, a wire screen element in the recess of the upper tank overlying the upper ends 10 of the wick, an auxiliary fabric wick overlying the wire screen element, a reservoir located in the upper tank, and a valved connection for permitting liquid to flow from the reservoir onto the auxiliary wick.

WILLIS H. THOMAS.
